UNITED STATES PATENT OFFICE.

DAVID G. MORGAN, OF SAN FRANCISCO, CALIFORNIA.

MACHINE FOR MAKING AUTOMOBILE-BUMPERS.

1,266,975.

Specification of Letters Patent. Patented May 21, 1918.

Application filed June 20, 1917. Serial No. 175,841.

To all whom it may concern:

Be it known that I, DAVID G. MORGAN, a citizen of the United States, residing at the city and county of San Francisco and State of California, have invented new and useful Improvements in Machines for Making Automobile-Bumpers, of which the following is a specification.

This invention relates to the manufacture of automobile bumpers and more particularly to a device for forming the same.

My object is to provide a simplified and improved machine for forming a spring metal automobile bumper of the type characterized by bent ends each having an eye.

The operation of forming the bumper consists, generally, of laying a heated metal bar in the machine and by means of a pressure die bending each end around a post, retaining said bent end in position and twisting it a quarter turn, and then curving the twisted end into the required shape to fit the front end of a side bar of an automobile frame.

One form which my invention may assume is exemplified in the following description and illustrated in the accompanying drawings, in which—

Figure 1 shows a plan view of a device embodying my invention.

Fig. 2 shows a sectional view taken on the line 2—2 of Fig. 1.

Fig. 3 shows a detail and inverted plan of the movable post about which the bar is bent to form the eye.

Fig. 4 shows a sectional view of the same.

Fig. 5 shows a detail view of the adjustable gage plate on the machine.

Fig. 6 shows a detail in perspective of the movable jaw of one of the bending dies and the detachable handle therefor.

Fig. 7 shows a perspective view of a portion of the eccentric lever for forcing the bending dies home and retaining them in closed position.

Fig. 8 shows a perspective view of the wedge-shaped impression member which fits between the jaws of the bending die.

Fig. 9 shows a detail perspective view of the twisting tool.

Fig. 10 shows a perspective view of the templet for curving the terminus of the bent end of the bar.

Fig. 11 shows a perspective view of the completed bumper.

Referring in detail to the accompanying

drawings, the machine comprises a base plate 10, at one or both ends of which is a set of bending dies each comprising a stationary jaw 11 formed with a curved outer end 12 and an indentation 13. Pivoted to the outer end is a movable jaw 14, angular in plan and having a curved inner end 15 indented at 16 and a right angularly disposed outer end 17. A post 18, carried by a swinging plate 19 and working in a slot 20, is positioned between the said jaws and a movable wedge-shaped impression block 21 also lies between said jaws. Preferably the latter is removably mounted upon the base plate, being held in position by means of a pin 22 entering an opening 23 in said plate.

A bar 24 of heated metal is laid in place on the base plate with its end lying between the stationary jaw 11 and the impression block 21 and projecting to one side of the machine, the movable jaw 14 being thrown back, as shown, to the right in Fig. 1 and the post 18 being moved to the outer end 80 of the slot 20. A handle 25 is fitted to the movable jaw 14 by means of pins 26 entering apertures 27 in the right angularly disposed end 17 of the jaw, and thereby the movable jaw is swung about bending the heated bar around the post 18 and forming an eye 28 therein. The movable jaw should be forced tightly home and held in this position during the subsequent operations and I provide a lever 29 with a fulcrum pin 30 to enter an aperture in the base plate and having an eccentric head 31 working against the movable jaw and capable of retaining the latter in closed position.

The outer end of the movable jaw operates with a stationary block 32 which is undercut or recessed to receive the bumper bar and retain the same securely in position while a twisting tool 33 having a bifurcated end 34 is applied to the projecting end of the bumper bar and given a quarter turn to form a twist 35 in said bar. Thereafter, and preferably by means of the twisting tool 33, the end of the bar is kinked or bent upwardly to allow a curved templet 36 to be placed beneath. This templet has one end resting against the block 32 and is clamped in position upon the base plate by means of a crank shaft 37 having a projection 38 to engage the forward end of the templet. The projecting end of the bumper templet is thereafter hammered or pressed down

upon the templet which gives it the required curvature to fit the front end of the side bar of an automobile frame. This templet varies in shape according to the automobile 5 frame for which the bumper is designed.

In laying out the bumper bar it is marked or punched at specified distances from the ends. These marks or apertures are used to gage the position of the bar in the press 10 by providing a bowed plate 39 adjustably secured to the base plate near the center thereof and having an attenuated end 40 to register with the mark on the bumper bar or enter an aperture 41 therein. The gage 15 plate is made of spring metal and shaped as shown to permit it to yield so that the shifting movement of the bumper bar in cooling may not be interfered with. By having said plate adjustably mounted, 20 bumpers of different lengths may be accommodated. Both ends of the base plate may be similarly equipped to form opposite ends of the bumper and many of the tools may be transferred from one end to the 25 other, as for instance the impression member 21, the handle 25, eccentric lever 29 and templet 36.

The described machine will form any desired form of bumper and is cheap to construct and inexpensive and easy to operate.

Various changes in the construction and arrangement of the several parts herein shown and described may be employed without departing from the spirit of my invention 35 as disclosed in the appended claims.

Having thus described my invention, what I claim and desire to secure by Letters Patent is—

1. A machine for forming spring metal 40 automobile bumpers of the type characterized by bent ends forming an eye, said machine comprising a post, means for bending the heated bumper bar around said post leaving the end projecting at right angles 45 to the body portion, said means comprising a die having pivotally connected jaws, one of said jaws being movable and the other stationary, means for manipulating the movable jaw, means for retaining said jaws in closed position, said movable jaw having a right 50 angularly disposed outer end, and a block against which said end presses the bumper bar whereby to retain the bar in place to permit it to be twisted.

2. A machine whereby a straight headed bar may be formed at each end with an eye and the end portions bent back upon the body portion and projected laterally at right angles thereto and formed with a twisted 60 and bowed terminus comprising a base plate, a set of bending dies at each end comprising an arcuately movable post and a stationary forming jaw and a movable jaw pivotally connected to the latter and swinging substantially concentric with the path of travel

of said post, said movable jaw having a handle by which it may be swung around the post compressing the bar into place, and an eccentric lever for forcing the movable jaw home and retaining it in such position for 70 subsequent operations.

3. A machine whereby a straight headed bar may be formed at each end with an eye and the end portions bent back upon the body portion and projected laterally at right 75 angles thereto and formed with a twisted and bowed terminus comprising a base plate, a set of bending dies at each end comprising a movable post and a stationary forming jaw and a movable jaw pivotally connected 80 to the latter, said movable jaw having a handle by which it may be swung around the post compressing the bar into place, an eccentric lever for forcing the movable jaw home and retaining it in such position for 85 subsequent operations, the outer end of the movable jaw being right angularly disposed, and a recessed block against which the bar is pressed by the outer end of the jaw and retained while a twist is imparted thereto. 90

4. A machine whereby a straight headed bar may be formed at each end with an eye and the end portions bent back upon the body portion and projected laterally at right angles thereto and formed with a twisted 95 and bowed terminus comprising a base plate, a set of bending dies at each end comprising an arcuately movable post and a stationary forming jaw and a movable jaw pivotally connected to the latter, said movable jaw having a handle by which it may be swung around the post compressing the bar into place, an eccentric lever for forcing the movable jaw home and retaining it in such position for 100 subsequent operations, the outer end of the movable jaw being right angularly disposed, and a recessed block against which the bar is pressed by the outer end of the jaw and retained while a twist is imparted thereto. 105

5. A machine whereby a straight headed bar may be formed at each end with an eye and the end portions bent back upon the body portion and projected laterally at right angles thereto and formed with a 110 twisted and bowed terminus comprising a base plate, a set of bending dies at each end comprising a movable post and a stationary forming jaw and a movable jaw pivotally connected to the latter, said movable jaw having a handle by which it may be swung around the post compressing the bar into place, an eccentric lever for forcing the movable jaw home and retaining it in such position for 115 subsequent operations, and a 120 gage plate mounted on the base plate adapted to enter an opening in the bar for centering it in relation to the bending dies. 125

6. A machine whereby a straight headed bar may be formed at each end with an eye 130

and the end portions bent back upon the body portion and projected laterally at right angles thereto and formed with a twisted and bowed terminus comprising a base 5 plate, a set of bending dies at each end comprising an arcuately floating post and a stationary forming jaw and a movable jaw pivotally connected to the latter, said movable jaw having a handle by which it may 10 be swung around the post compressing the bar into place, means for retaining the jaws in closed position, and means for rigidly holding the bar adjacent to its end while bending the projecting end of the bar upwardly and imparting a quarter twist thereto.

7. In a metal working machine, a rigid forming jaw, a movable forming jaw pivoted in relation thereto and between which 20 jaws a metal blank may be bent, an arcuately movable pin adapted to be forced toward the fixed jaw and therebetween by the swinging movement of the pivoted jaw and along a path of travel substantially concentric with the axis thereof, thereby causing 25 an eye to be formed by the metal blank at the point at which it is bent.

8. In a metal working machine, a fixed jaw having a forming face against which a 30 metal blank is to be pressed, a movable forming jaw pivoted at one end to one end of the fixed jaw whereby said blank may be bent upon itself as the movable jaw swings toward the fixed jaw, and a wedged-shaped impression block pivotally mounted in relation to the fixed and movable jaws and having a freely swinging end adapted to project between the jaws and the doubled portions of the blank whereby said portions 35 may be held apart and caused to conform to the faces of the jaws as they are drawn together.

9. In a metal working machine, a fixed jaw having a forming face against which a 40 metal blank is to be pressed, a movable forming jaw pivoted at one end to one end of the fixed jaw whereby said blank may be bent upon itself as the movable jaw

swings toward the fixed jaw, detachably pivoted means whereby the double portions of the blank may be held apart from each other and caused to conform to the faces of the two jaws as they are forced together and whereby the pressure exerted by the movable jaw will be uniformly distributed to the 55 portions of the blank against the forming faces of both jaws.

10. In a metal working machine, a pair of forming jaws pivoted in relation to each other between which a metal blank may be 60 bent and a freely moving impression block interposed between said jaws and pivoted in relation thereto whereby the pressure exerted to draw the jaws together will act to force the metal blank outwardly against the 65 adjacent forming faces of the jaws.

11. In a metal working machine, a pair of forming jaws pivoted in relation to each other between which a metal blank may be 70 bent, a freely moving impression block interposed between said jaws whereby the pressure exerted to draw the jaws together will act to force the metal blank outwardly against the adjacent forming faces of the 75 jaws, and an arcuately swinging pin where by an eye may be formed at the bend of the blank and between the jaws.

12. In a metal working machine, a fixed forming jaw, an arcuately moving pin adjacent one end thereof, a movable forming 80 jaw pivoted to the same end of said fixed jaw and adapted to swing partially around the pin whereby a metal blank may be bent around the pin and a movable impression block pivotally mounted in relation to said 85 jaws whereby the pressure upon the pivoted jaw will cause the blank to assume the contour of the forming faces of the two jaws.

In testimony whereof I have hereunto set my hand in the presence of two subscribers. 90
